ELECTROMAGNETIC RELAY

Hans-Fredi Schwartz and Otto Baier, Berlin, Germany, assignors to C. Lorenz Aktiengesellschaft, Berlin-Tempelhof, Lorensweg, Germany, a company

Application September 7, 1938, Serial No. 228,756
In Germany August 13, 1937

7 Claims. (CL 200—87)

The present invention relates to electro-magnetic relays, and more specifically to the type of relays which operate in vacuum.

It is a well known expedient to place the contacts of an electromagnetic relay within a vacuum container in order to avoid troubles in operation which may occur on account of an oxidation of the contact elements, and to secure a non-arcing contact make and break even at very high potentials. Certain difficulties arise when such relays are adapted to operate at a low atmospheric pressure, for example on aircraft at great heights above the earth's surface, where flash-over phenomena in the shape of spray discharges occur at high potential operation between the high voltage conducting lead-in conductors and the field coil of the relay armature which is maintained at the earth's potential. Such troubles are attributable at a non-uniformity in the potential distribution between these elements so that the electric lines of force are subjected to such concentration at certain points that a discharge takes place.

The invention has for its object to avoid the aforesaid disadvantages, and this is carried out in accordance with the main feature of the invention by providing the vacuum vessel of such electromagnetic relays with a shielding surface which is maintained at earth's potential. This shielding may, according to a further feature of the invention, be a rim of silver applied on the inner surface of an annular torus-shaped extension of the vacuum relay.

The invention will be more readily understood from the following description taken in conjunction with the accompanying drawing, in which—

Fig. 1 is a longitudinal section through an electromagnetic vacuum relay according to the invention, Fig. 2 is a cross section on the line 2—2 of Fig. 1, while Fig. 3 is a further cross section on the line 3—3 of Fig. 1.

The vacuum relay consists of a glass vessel or envelope 1, an intermediate portion 2, and a closing member or cover 3, on which latter the actual relay system is mounted. This system comprises, by way of an example, two rods 4 and 5 of insulation sealed to the cover 3 and these rods serve as supports for the necessary contacts and switching elements of the vacuum relay. The movable armature 7 of this relay is carried from the upper end, or end remote from cover 3, of the rod 5 by the agency of a clip 6 and consists of a hinge member 8 movably attached to the clip 6 and a flat strip 9 of

insulation, such as ceramic, for example, on which the magnetization responsive means 10 of the electromagnetic portion are fixed by means of member 21. The contact elements 11 which perform a make and break of the load circuits are located adjacent to the lower end, or end near cover 3, of the armature 7. The load circuit or circuits are connected to the relay device partially over the lead-in conductor 12 at one end of the relay and this conductor is connected to the contact element 14 and partially over leads 13 sealed in the cover 3 at the opposite end of the envelope. One of the leads 13 is connected to the fixedly mounted contact element 15 and the other lead is connected to a movable contact element 11 of the armature. The magnetization responsive means 10 of said armature are articulated so as to provide a small space between these means and the cooperating cores 16 of the relay magnet energized by windings 23 and 24.

In operation magnetic fields produced by electromagnets 16 act on the magnetization responsive members 10 and move the armature towards points 14 or 15 depending on the magnet energized or polarity of energization thus completing external circuits which may be connected to lead-in conductors 12 and 13. The electromagnets 16 may be energized by any suitable source.

The intermediate portion 2 of the relay device carries a particular torus-shaped extension 17 of annular form, the inner surface 18 of which according to one feature of the invention is provided with a conductive coating of silver, for example, which may be applied by spraying or similar methods. A cylindrical member 19 is soldered to the heretofore mentioned metal coating and serves as a guide and a support for the relay device in its fitting 20 in which the cores of the relay magnet are mounted. The silver coating may in the case of need be extended along member 2 toward the glass envelope or along the envelope as so far as approximately to the cores of the magnet. The fitting 20 and the cylindrical member 19 of the vacuum relay are maintained at earth's potential, while the leads 13 conduct high tensions. Investigations have proven that in the absence of such shielding means flash-over phenomena inevitably occurs over the glass walls between the magnet coils maintained at earth's potential and the high tension conducting lead-in conductors of the vacuum relay. Such flashing-over phenomena are reliably eliminated by the provision of the metallic coating according to the invention.

The closing member or cover 3 may, if desirable, be provided with a small torus-shaped annular projection 25 which is likewise coated with a layer of silver 22. This layer is then electrically connected to one of the lead-in conductors 13 of the vacuum relay by lead 26. Both lead-in conductors and this last mentioned silver coating are then maintained at the same potential when the vacuum relay is operative, so that no electric field is set up therebetween. This expedient still more enhances the safety against flash-over troubles. The connecting leads and their connecting points are thus rendered free of corona effects.

What is claimed is:

1. A vacuum type electromagnetic relay comprising a vacuum vessel member, a cover member, and an intermediate member rigidly jointed between said vessel member and said cover member, an armature assembly within said vessel member, contact means operatively associated with said armature, lead-in conductors for said contact means, at least one of said conductors extending through the cover member, magnetic means external to said vessel member for operating said armature assembly, said magnetic means being spaced from said intermediate member, and a shield in the shape of an annular metallic coating encircling one of said members.

said shield being positioned between said lead extending through said cover member and said magnetic means.

2. A vacuum-type electromagnetic relay according to claim 1 wherein said shield encircles said vessel member.

3. A vacuum-type electromagnetic relay according to claim 1 wherein said shield encircles said cover member.

4. A vacuum-type electromagnetic relay according to claim 1 wherein said shield encircles said intermediate member.

5. A vacuum-type electromagnetic relay according to claim 1 wherein said vessel member is made of glass, said intermediate member and said cover member are made of strongly refractory material, and said armature assembly and said contact means are mounted on said cover member.

6. A vacuum-type electromagnetic relay according to claim 1 wherein said shield is a coating of silver.

7. A vacuum-type electromagnetic relay according to claim 1 further comprising an annular torus-shaped extension on said intermediate member, said shield being applied to said extension.

HANS-FREDI SCHWARTZ.
